ATTORNEY.

UNITED STATES PATENT OFFICE.

DAVID H. CUNNINGHAM, OF ELIZABETH, NEW JERSEY.

BUTTON-HOLE CUTTER.

SPECIFICATION forming part of Letters Patent No. 379,007, dated March 6, 1888.

Application filed May 11, 1887. Serial No. 237,897. (No model.)

To all whom it may concern:

Be it known that I, DAVID HENRY CUNNINGHAM, a citizen of the American Republic, and a resident of Elizabeth, in the county of Union, State of New Jersey, have invented 5 certain new and useful Improvements in Button-Hole Cutters, of which the following is a full, clear, and exact specification thereof.

My invention relates to a novel device 10 adapted for cutting button-holes in fabrics of various kinds. Said device will be fully described hereinafter.

The first part of my invention consists of a spring-metal strip provided with guides at 15 one end adapted to engage with a corresponding shape made on the body of a base-plate. The foremost portion of this spring-metal strip is bent so that its contour will form a portion of a circle or curve, its end forming a bearing 20 for an arbor carrying a rotary knife, which may be of various shapes, depending, of course, upon the style of button-hole desired.

The second part of my invention consists of a vertically-projecting lug or standard, which 25 may be integral or otherwise connected with the base-plate, hereinbefore referred to. Said lug or standard forms a bearing for one end of a horizontally-arranged screw, the other end of which plays in a perforation made in the 30 vertical portion of the spring-metal strip. Upon the horizontal screw is mounted a screw-nut adapted to regulate the distance which the spring-metal strip (which I will call the "rotary-knife carriage") may be required to 35 travel.

The third part of my invention consists of a retracting-spring having one end connected with the lug or standard of the base-plate, the other end connected with the foremost end of 40 the rotary-cutter carriage. I may use two or more springs arranged on each side of the rotary cutter in lieu of a single spring.

In the accompanying drawings, Figure 1 represents a side elevation of the device complete. Fig. 2 represents a transverse section taken on line $x-x$, in which is shown the manner of mounting the end of the rotary-cutter carriage upon the base-plate. Fig. 3 represents a transverse section taken on line $y-y$, 45 looking in the direction indicated by the ar-

row. This view shows the cloth or fabric guide and the marker connected therewith.

Similar letters refer to similar parts throughout all the drawings, in which—

a represents the spring-metal strip forming 55 the main body of the rotary-cutter carriage. The end of the strip *a* is provided with the guides *b*, adapted to engage with the base-plate *c*. The forward portion of the said strip *a* is provided with the bearings *d*, adapted to receive 60 the arbor *e*, carrying the rotary cutter *f*. The base-plate *c* is provided with the lug or standard *g*, the upper portion of which carries one end of the horizontal screw *h*, while the other end plays in a perforation made in the 65 vertical portion *i* of the said strip *a*. Upon this screw *h* is mounted a corresponding threaded nut, *k*, which may be moved to and fro when regulating the travel of the rotary-cutter carriage. To the upper part of the lug 70 *g* is fastened one end of the retracting-spring *g'*. The other end is connected with the rotary-cutter carriage. The base-plate *c* is also mounted with a sliding frame, *l*, provided with a cloth or fabric guide, *m*, and adjustable 75 marker *n*. The base-plate is still further provided with a downwardly-projecting lug or flange, *o*, the object of which is to butt against the edge of a table when operating the device. In lieu of this flange or lug *o*, I may use a screw 80 clamp or grip, which is, however, unnecessary to illustrate.

Modus operandi: The fabric is laid upon the base-plate *c*, and, resting against the guide *m*, the operator presses down upon the knob *p*, 85 whereby the edge of the cutter *f* is forced down upon the fabric. The carriage is then pushed forward, cutting the hole desired in the fabric. The pressure and resistance are then removed from the carriage and spring *g'*, the former of 90 which is carried back to its normal position by said retracting-spring *g'*. The screw *h* is of course mounted with a detent or stop, which prevents the spring-metal strip *a* from moving off of the base-plate. The fabric is moved 95 laterally until the hole shall have reached the indicating-point *r* of the marker *n*, when the same operation is repeated until the entire number of button-holes shall have been cut.

Having thus described my invention, what 100

I claim as new, and desire to secure by Letters Patent, is—

1. The combination, with a button-hole cutter herein described, of the sliding carriage having guides integral therewith adapted to engage with the base-plate *c*, the forward end of the said carriage carrying a rotary cutter, substantially as shown and described.

2. The combination, with a rotary button-hole cutter herein described, of the retracting-spring *g'*, having one end thereof connected with the lug *g* of the base-plate *c*, the other end of said retracting-spring connected with the forward end of the sliding carriage, substantially as shown and described.

3. The combination, with the button-hole cutter herein described, of the horizontal screw having one end connected with the vertical lug or standard of the base-plate, the other end playing in a perforation made in the sliding carriage, and the threaded nut mounted on said horizontal screw, the whole of which forms the distance-regulator, substantially as shown and described.

In testimony that I claim the foregoing I have hereunto set my hand.

DAVID H. CUNNINGHAM.
